(57) **CLAIM**

The ornamental design for a transponder housing, as shown and described.

DESCRIPTION

FIG. 1 is a rear perspective view of a transponder housing showing my our new design.

FIG. 2 is a front elevational view thereof.

FIG. 3 is a bottom side elevational view thereof.

FIG. 4 is a left side elevational view thereof; and,

FIG. 5 is a rear elevational view thereof.

The broken lines in the figures are for illustrative purposes only and form no part of the claimed design.
